INHIBITION OF DECOMPOSITION OF AMALGAM

Robert S. Karpik, Midland, Mich., assignor to The Dow Chemical Company, Midland, Mich., a corporation of Delaware

Filed Aug. 14, 1958, Ser. No. 755,073

3 Claims. (Cl. 204—99)

The invention relates to inhibiting the decomposition of an amalgam. More particularly, it relates to inhibiting the decomposition and/or reaction of an alkali metal amalgam during the production thereof in the electrolyzer chamber of a chlorine cell which employs a mercury cathode in the electrolysis of an alkali metal chloride electrolyte. Reactivity of the alkali metal amalgam during electrolysis, although appearing to consist of both decomposition and complex reactions with the aqueous electrolyte, will be referred to hereinafter merely as the decomposition thereof for simplicity of expression.

A conventional cell and method of producing chlorine is to electrolyze an alkali metal chloride brine, e.g., an aqueous solution of NaCl, to yield chlorine gas at the anode and the alkali metal as an amalgam on a mercury cathode, the amalgam being subsequently decomposed in the presence of water in a separate chamber or chambers to yield the alkali metal hydroxide and hydrogen as end products and mercury for re-use in the electrolysis. In the electrolytic production of an alkali metal hydroxide and chlorine employing such cell and method, there has heretofore been a loss in efficiency, an appreciable part of which is due to the decomposition of the alkali metal amalgam during the electrolysis. A mercury cell, of the type described in U.S. Patent 2,719,117, or 2,836,551 serves to illustrate the mercury cathode type chlorine cell and mode of operation of such cell for the production of an alkali metal amalgam and chlorine.

Attempts have been made to improve the efficiency of mercury cathode-type chlorine cells by the addition of inorganic stannates, borates, silicates, or pyrophosphates to the electrolyte. These attempts have not been sufficiently successful in the inhibition of the decomposition of the alkali metal amalgam to justify their being adopted generally in the production of chlorine employing such cells.

There exists, therefore, a desideratum in the art of chlorine production by the electrolysis of an alkali metal chloride brine, wherein the alkali metal is recovered as an amalgam on a mercury cathode, for an improved electrolyte and method employing such electrolyte which is substantially more efficient due to the inhibition of the decomposition of the alkali metal amalgam during the electrolysis of the brine.

It is an object of the invention to provide such an improved electrolyte and a method of use thereof wherein the decomposition of the amalgam being formed is suppressed or inhibited thereby improving the efficiency of the electrolytic production of mercury cathode type cells.

The method and means by which this and related objects of the invention are attained is made clear in the ensuing description and are particularly defined in the appended claims.

The invention is an improved electrolyte for and method of producing chlorine and an alkali metal amalgam by the electrolysis of an alkali metal chloride brine wherein a water-soluble organic hydroxy compound is

2

admixed with the alkali metal chloride brine employed in such cells. The compounds which can be employed in the practice of the invention as additives to such brine electrolytes are the alkylene glycols, mono- and poly-alkylene glycol monoethers, halo-substituted derivatives of such glycols and ethers, epihalohydrins, and higher molecular weight saturated alcohols having at least 5 carbon atoms. Examples of such hydroxy compounds are dipropylene glycol, epichlorohydrin, cyclohexanol, 2-methoxyethanol, 2(2-ethoxyethoxy)ethanol, ethylene glycol, 2-ethoxyethanol and ethylene chlorohydrin. The hydroxyl group is thought to be an essential substituent of the inhibitor employed according to the invention. Epihalohydrins are considered to be within the class because they assume characteristics of such hydroxy compounds as the glycols and their ethers, apparently due to hydrolysis at the oxygen bridge. Lower molecular weight alcohols, however, cannot be employed because of their tendency to react in a similar manner to, although less violent than, water with an alkali metal amalgam. Hydroxyl-containing compounds having acidic properties, e.g., carboxylic acids, phenol, cresols, and the like, cannot be used. The alcohol should contain at least five carbon atoms to be sufficiently unreactive with the amalgam. The additives, which include both liquids and solids usually exist under normal conditions as liquids and may be advantageously stirred into the electrolyte either prior to the electrolysis or intermittently or continuously during the electrolytic process to achieve the desired effect of their use in accordance with the invention. Each of the additives is a well-known, readily accessible, and relatively inexpensive material. The amount of additive to employ is not sharply critical and may be calculated either as a percent by volume or percent by weight based on the volume or weight of brine. For convenience, the percent by volume is usually used since the specific gravity of the additive is not greatly different from that of the brine. The amount employed in the practice of the invention is small. At least 0.001 percent by volume should be employed. It is recommended that between 0.005 and 0.03 percent by volume be employed. Greater amounts, e.g., .05 percent or more may be employed but are considered uneconomical. 0.02 percent appears to be about the optimum amount to add, based on the volume of the alkali metal chloride brine.

An apparatus of the type schematically shown in Figure 1 was employed to demonstrate the effects of the water-soluble organic hydroxy compounds on the decomposition rate of a sodium amalgam when added to an alkali metal chloride brine in a primary cell in which an alkali metal amalgam and pieces of graphite serve as the anode and cathode, respectively, of the cell. Decomposition efficiency is a measure of the decomposition of the alkali metal amalgam in the testing apparatus used. It is 100 percent, as shown in Figure 2, when no inhibitor is present. Decomposition efficiency is defined as:

$$\frac{\text{Volume of H}_2 \text{ evolved per second from inhibited brine}}{\text{Volume of H}_2 \text{ evolved per second from substantially pure brine}} \times 100\%$$

The rate of decomposition of a prepared sodium amalgam in a specific concentration of sodium chloride brine was ascertained by determining the volume of hydrogen evolved during a measured period of time employing the apparatus shown in Figure 1. The decomposition efficiency of the sodium amalgam in the NaCl brine according to the invention as thus determined is set out in graphic form in Figure 2.

The apparatus of Figure 1 comprises Pyrex jar 10,

cylindrical dish 12 resting on the floor of the jar, sodium amalgam feed tube 14 provided with funnel 16 leading into dish 12 and vertically positioned graduated cylinder 18 having dome-shaped base 20 resting on the bottom of jar 10, which forms a gas-collecting means about dish 12, and having petcock assembly 22 and nipple 24 in the upper part thereof for the attachment of an exhaust means. Sodium amalgam 26 is shown on the floor of dish 12. In dish 12 and partially submerged in amalgam 26 is graphite anode 28 consisting of two vertically positioned $\frac{1}{4}$ " plates separated by an insulator. (A single piece of graphite might have been employed, but would have been less efficient.) Sodium chloride brine 30 is shown in Pyrex jar 10 and in tube 14 at the same level as in jar 10, and in tube 14 at the same level as in jar 10, and in cylinder 18 extending to the top thereof, the brine

gam in an alkali metal chloride bath by the presence of an inhibitor in accordance with the invention was then shown in the examples below by following the procedure and employing the apparatus and the same concentration of sodium chloride brine as in the conditioning steps above except that in each of the examples, an increasing amount of an inhibitor was added to the brine, according to the invention, contained in jar 10 as shown in Figure 1. The amounts of the inhibitor were increased up to 0.02 percent by volume based upon the volume of sodium chloride brine. The effect on decomposition efficiency is set out in table form in Table I for additions of 0.01 and 0.02 percent by volume of inhibitor and graphically in Figure 2 for the additions shown, up to 0.02 percent. The lower the decomposition efficiency, in general, the more effective was the inhibitor employed in the brine.

TABLE I

Effect on decomposition of amalgam in brine by presence of inhibitors

Example	Inhibitor Added to the Brine	Formula of Inhibitor	Properties of Inhibitors		Decomposition Efficiency	
			Mol. Wt.	Density at 20° C.	Percent Inhibitor by Volume	
					0.010	0.020
1.	Dipropylene glycol	$(\text{CH}_3\text{CH}_2\text{OHCH}_2)_2\text{O}$	134.17	1.022	51	48
2.	Epichlorohydrin	$\text{CH}_2-\text{CH}(\text{O})-\text{CH}_2-\text{Cl}$	92.53	1.801	64	58
3.	Cyclohexanol	$\text{C}_6\text{H}_{11}\text{OH}$				
4.	2-methoxyethanol	$\text{CH}_3\text{OCH}_2\text{CH}_2\text{OH}$	76.09	0.966	75	64
5.	2-(2-ethoxyethoxy) ethanol	$\text{C}_2\text{H}_5\text{OCH}_2\text{CH}_2\text{OCH}_2\text{CH}_2\text{OH}$	134.17	0.9902	76	68
6.	Ethylene glycol	$\text{HOCH}_2\text{CH}_2\text{OH}$	62.7	1.1155	76	75
7.	2-ethoxyethanol	$\text{C}_2\text{H}_5\text{OCH}_2\text{CH}_2\text{OH}$	90.12	0.9311	88	76
8.	Ethylene chlorohydrin	$\text{ClCH}_2\text{CH}_2\text{OH}$	80.52	1.213	93	88

being drawn up into 18 by exhausting the air therefrom as explained hereinafter.

The practice of the invention will be illustrated by examples showing the rate of decomposition of an amalgam in a sodium chloride brine containing an inhibitor according to the invention in contrast to the rate of decomposition of the sodium chloride brine to which no inhibitor is added.

To illustrate the practice of the invention, the following procedure was followed employing an apparatus of the type shown in Figure 1:

The graphite cathode was first conditioned by repeating the following series of conditioning steps several times until the volume of hydrogen gas evolved per minute was stabilized, i.e., was substantially uniform:

Graphite cathode 28 was placed in position in dish 12. A brine consisting of 300 grams of chemically pure sodium chloride dissolved in enough water to make five liters was placed in jar 10. Petcock 22 was opened and vacuum applied at nipple 24 thereby exhausting cylinder 18 of air and causing the brine to rise in cylinder 18, as shown, until it reached petcock 22 at which time petcock 22 was closed and the vacuum discontinued. The temperature of the brine was 25° C.

250 grams of sodium amalgam consisting of 0.28 percent by weight of sodium, the balance being mercury, were then poured into funnel 16 and down tube 14, collecting at the bottom of dish 12 as shown.

The rate of hydrogen gas collecting in the graduated upper portion of cylinder 18 per minute became stabilized at an average of 0.34 milliliter per minute.

The effect on decomposition of an alkali metal amal-

A study of Table I and Figure 2 shows the decomposition efficiency of the sodium amalgam uninhibited brine to be 100 percent and that additions of various inhibitors to the pure brine containing the amalgam in accordance with the invention substantially lowered this efficiency by inhibiting the decomposition thereof. Figure 2 also shows that when as little inhibitor was added as 0.001 percent by volume based on the volume of NaCl brine, the inhibiting effect on the decomposition of the amalgam was readily apparent and that this effect became more marked, i.e., the decomposition efficiency continually lessened with increased amounts of the inhibitor up to 0.02 percent by volume, except for cyclohexanol which was somewhat more effective than the other inhibitors in small amounts (on the order of 0.001 percent) but which leveled off with a slightly lessening inhibiting effect at about 0.015 percent. A further study of Figure 2 shows that an amount of an inhibitor of at least 0.01 percent by volume should be added, that 0.02 percent appears to be an optimum amount to add, and that in general some increased inhibiting effect continues beyond an amount of 0.02 percent but by extrapolation of the curves such increased effect appears inconsequential beyond say 0.03 percent, and clearly uneconomical beyond about 0.05 percent by volume of the alkali metal chloride bath.

Further examination of the table and Figure 2 shows the relative diminution of decomposition of the amalgam when the different inhibitors are used in accordance with the invention. For example, when 0.02 part by volume of dipropylene glycol, based upon the volume of the brine, is added thereto, the decomposition is reduced by 70
75
80
85
90
95

52 percent. The least effective of the additives of the

invention employed was ethylenechlorohydrin which showed a diminution of the decomposition of the sodium amalgam by 12 percent.

The presence of the OH radical in the organic group appears essential to the practice of the invention. Furthermore, the presence of two OH radicals such as in the case of the dipropylene glycol, appears to enhance the beneficial effect upon the suppression of the decomposition of the sodium amalgam.

The effective inhibition of the decomposition of an alkali metal amalgam, as demonstrated by the example, has direct application when the inhibitor is added to a mercury cathode type chlorine cell employing an alkali metal chloride electrolyte.

To illustrate the invention, 0.02 volume percent of dipropylene glycol based on the volume of the NaCl brine was added thereto in the electrolyzer chamber of a cell in a commercial chlorine-producing unit. The efficiency of the cell rose 7 percent over its production efficiency prior to such addition. After 3 days the production efficiency decreased to its earlier efficiency. 0.02 volume percent of dipropylene glycol was again added to the cell upon which the production efficiency again rose by 7 percent.

The examples above show that the presence in the brine used in a mercury cathode type cell of a water-soluble organic hydroxy compound illustrated by alkylene glycols, mono- and polyalkylene glycol monoethers, halo-substituted glycols and ethers and such hydroxy-forming compounds as epichlorohydrin, and high molecular weight saturated alcohols, suppress or inhibit the decomposition and/or reaction of the alkali amalgam formed at the cathode. Such decomposition during electrolysis, when un-

inhibited, decreases the efficiency of the cell to a point where it seriously affects the output. Markedly raising the efficiency of such cells by the addition of a readily available, safe, low-cost inhibitor has an extensive economic impact upon chlorine and alkali hydroxide production.

Having described the invention, what is claimed and desired to be protected by Letters Patent is:

1. The method of producing chlorine by electrolysis of an alkali metal chloride brine employing a mercury cathode consisting of admixing with the brine between 0.001 and 0.05 percent by volume of a water-soluble organic hydroxy compound unreactive with alkali metal amalgams selected from the class consisting of alkylene glycols, mono- and polyalkylene glycol monoethers, halo-substituted derivatives of said glycols and ethers, epihalohydrin, and higher molecular weight saturated alcohols containing at least 5 carbon atoms.
2. The method according to claim 1, wherein the organic hydroxy compound is dipropylene glycol.
3. The method according to claim 2, wherein the dipropylene glycol is admixed in an amount between 0.01 and 0.03 percent by volume based upon the volume of brine.
